UNITED STATES PATENT OFFICE.

JOHN MAIER AND THURMAN RICE, OF CANTON, OHIO.

DESIGN FOR A TOY.

58,792.

Specification for Design.

Patented Aug. 30, 1921.

Application filed April 29, 1921. Serial No. 465,540. Term of patent 14 years.

To all whom it may concern:

Be it known that we, JOHN MAIER and THURMAN RICE, both citizens of the United States, residing at Canton, in the county of Stark and State of Ohio, have invented a new, original, and ornamental Design for Toys, of which the following is a specification, reference being had to the accompanying drawing, forming part hereof.

The figure is a perspective view of the toy, showing our new design.

We claim:—

The ornamental design for a toy, as shown.

JOHN MAIER.
THURMAN RICE.
